UNITED STATES PATENT OFFICE.

DAVID B. WHISTLER, OF DAYTON, OHIO, ASSIGNOR TO THE RECORDING AND COMPUTING MACHINES COMPANY, OF DAYTON, OHIO, A CORPORATION OF OHIO.

OPERATING MECHANISM FOR FARE-REGISTERS.

No. 839,684.

Specification of Letters Patent.

Patented Dec. 25, 1906.

Application filed September 20, 1906. Serial No. 335,465.

To all whom it may concern:

Be it known that I, DAVID B. WHISTLER, a citizen of the United States, residing at Dayton, in the county of Montgomery and State of Ohio, have invented certain new and useful Improvements in Operating Mechanism for Fare Registers and Recorders, of which the following is a specification, reference being had therein to the accompanying drawings.

10 My invention relates to operating mechanism for fare registers and recorders, and relates more particularly to mechanism for operating that class of fare registers and recorders which are adapted to register and 15 record a variety of different fares and are provided with mechanism for first setting the mechanism to indicate a particular fare and then operating the mechanism to register that fare, such a register and recorder being disclosed in the application of W. I. 20 Ohmer, Albert J. Kirchner, and John W. Hill, filed December 16, 1905, Serial No. 292,068.

The object of the invention is to provide such an operating mechanism that will enable 25 the operator to set the recording mechanism and operate the same to register and record the fare without removing his hand from the operating device, thereby greatly facilitating the registration of these fares and enabling 30 the same to be registered with much greater speed and accuracy.

To this end my invention consists of the construction hereinafter to be described and then more fully pointed out in the claims.

35 Referring to the accompanying drawings, Figure 1 is a side elevation of my device. Fig. 2 is a top plan view of the same. Figs. 3 and 4 are detail views of the indicator-plate and the indicator. Fig. 5 is an end elevation 40 of my device. Fig. 6 is a detail view of the handle and its operating mechanism. Fig. 7 is a transverse sectional view.

In the drawings the reference-numeral 1 indicates a fare-register of any approved 45 type, preferably that mentioned above, which contains mechanism for setting the recording mechanism and registering the several fares, which setting and recording mechanism is connected, by means of a rod 2 and universal joints 3 and 4, with the operating-rod 5, which is journaled in brackets 6, secured to any suitable support, preferably

the side of the car. Secured at suitable intervals along the operating-rod 5 are indicator-plates 7, which may be either rigidly secured to the bracket 6 or may be mounted on the operating-rod 5 and rotated therewith. These indicator-plates are divided longitudinally into equal sections, each section containing the designation of a particular kind of fare, such as "Five cents," "Tickets," "Passes," &c. An indicator-rod 8 extends substantially parallel with the operating-rod 5 and is slidably mounted in bearings formed in brackets carried by the operating-rod, as hereinafter described. This rod is provided at intervals of its length, adjacent to the indicator-plate 7, with indicators or pointers 10, which are adapted to travel over the face of said indicator-plate and indicate thereon the fare which the registering mechanism is set to register. This indicator may be of any suitable construction; but I prefer that disclosed in the drawings, Figs. 3 and 4, in which it consists of a substantially rectangular plate 75 11, carried by a collar 12, which is rigidly secured to the rod 8 by a set-screw 13 and has its walls adapted to surround the particular designation which it is desired to indicate. Secured to the upper and lower walls of the 80 rectangular frame portion 11 are pointers 14, which are so arranged that at least one of the pointers is within the range of vision of the passengers at all times during the movement of the indicator as it moves with the rod 8 85 around the axis of the operating-rod 5, which movement will be hereinafter described.

Rigidly secured to the operating-rod 5, adjacent to the indicator-plate 7, are brackets 15, each of which is provided with a bearing-aperture 16, in which is journaled the upper portion 17 of the operating-handle 18, which extends beyond said bracket and is provided with a gear-wheel 19. Each bracket 15 is provided with a pair of lugs 20, having apertures 21 at substantially right angles to the aperture 16, in which apertures the indicator-rod 8 is mounted and in which said rod has a sliding movement. This rod 8 is provided with gear-teeth 22 for a portion of its length 95 immediately adjacent to said operating-handle, which are adapted to be engaged by the gear-wheel 19, carried by said handle, and to impart a longitudinal sliding movement to

said rod when the handle 18 is rotated in its bearing 16, thereby carrying the indicator 10 over the face of the indicator-plate 7.

Rigidly secured to the end of the operating-rod 5 adjacent to the fare-register is a bracket 23, adapted to rotate therewith and provided with two upwardly-extending arms 24, having bearing-apertures 25 formed therein at substantially right angles to the operating-rod 5. Mounted within the bearings 25 is a shaft 26, connected at one end with the universal joint 4 of the operating-rod 2 and provided with a gear-wheel 27, engaging with the rack 28, mounted on the indicator-rod 8. This rack may be of any suitable description; but I prefer that shown in the drawings, in which it consists of a longitudinally-slotted rack-bar mounted at one end in a bracket 29, which is rigidly secured to the rod 8, and supported at its other end by a guide-lug 30, extending from the bracket 23 through the longitudinal slot 31 and serving as a guide for said rack-bar.

The operating-rod 5 is provided with one or more springs 32, adapted to return the operating mechanism to its normal position after a fare has been registered. These springs may be of any suitable construction; but I prefer that shown in the drawings, in which the spring 32 is coiled about the operating-rod 5 and secured at one end in an aperture 33 in the bracket 6 and at its opposite end in a collar 34, secured on the operating-rod 5.

From the foregoing description the operation of my device will be readily understood. When it is desired to register a fare, the operator grasps the handle 18 and rotates the same about its longitudinal axis, thereby revolving the gear-wheel 19 and imparting a longitudinal movement to the rod 8. As this rod moves longitudinally it carries with it the bar 28, which engages the gear-wheel 27, which is carried by the shaft 26, mounted in the bracket 23, thereby rotating said shaft and the operating-rod 2. At the same time the rod carries the indicator 10 along the face of the indicator-plate 7, said pointers of said indicator indicating the fare which the registering mechanism is set to register. When this indicator is in position over the designation of the proper fare, the operator pulls the handle 18 toward him, thereby rotating the shaft 5 about its longitudinal axis and causing the arms 24 of the bracket 23 to move rearwardly, thereby imparting a longitudinal movement to the rod 2, which in turn operates the registering mechanism in the register 1. When the registration is completed, as indicated by the ringing of the bell in the register, the handle is released and returns automatically to its normal position.

The setting and registering mechanism within the register 1 are so arranged that the handle 18 is locked against an outward move-

ment around its horizontal axis at all times save when the pointer on the indicator 10 is in alinement with the fare designation on the indicator-plate 7, at which times the handle is free to move forward; but as soon as it has begun its forward movement it is locked against rotary movement on its longitudinal axis. The gear-wheel 19, carried by the handle 18, and its rack 22 may be so arranged relatively to the gear 27 and rack 28 that the gear 27 and its shaft 26 will make any desired number of revolutions to a single revolution of the handle 18, the present arrangement being such that a single revolution of the handle 18 about its longitudinal axis will operate to move the setting mechanism through the entire list of fares and likewise move the indicator 10 the full length of the indicator-plate 7.

I wish it to be understood that I do not desire to be limited to the exact details of construction shown and described, for obvious modifications will occur to a person skilled in the art.

Having thus fully described my invention, what I claim as new, and desire to secure by Letters Patent, is—

1. In an apparatus of the character described, the combination, with a register, an actuating medium and a single operating mechanism, of means for actuating said medium thereby actuating said mechanism connecting said actuating medium with said register to set said register to indicate a particular fare and to operate the same to register that fare, substantially as described.

2. In an apparatus of the character described, the combination, with a register, an actuating medium and a single operating mechanism connecting said actuating medium with said register, of means for actuating said medium to impart two distinct movements to said operating mechanism, one to set said register to indicate a particular fare and the other to operate the same to register that particular fare, substantially as described.

3. In a device of the character described, the combination, with a register, an actuating medium and an operating mechanism connecting said actuating mechanism with said register, of means for actuating said medium to impart a rotary movement to said operating mechanism to set said register to indicate a particular fare and imparting a longitudinal movement thereto to operate the same to register that particular fare, substantially as described.

4. In an apparatus of the character described, the combination, with a register, an actuating medium and an operating mechanism connecting said actuating medium with said register, of a single means for actuating said means to impart two distinct movements to said operating mechanism, one to

- set the register to indicate a particular fare and the other to operate the same to register that particular fare, substantially as described.
5. In an apparatus of the character described, the combination, with a register, an actuating medium and an operating mechanism connecting said actuating medium with said operating mechanism, of an operating-rod and connected to said operating mechanism, having two distinct movements, and operatively connected to said operating mechanism, and means carried by said member for imparting said movements to said operating mechanism, substantially as described.
- 10 6. In an apparatus of the character described, the combination, with a register, and an operating mechanism therefor, of an operating-handle adapted to be rotated about its longitudinal axis to impart a rotary movement to said operating mechanism and adapted to be rotated about a transverse axis to impart a longitudinal movement to said operating mechanism, substantially as described.
- 15 7. In an apparatus of the character described, the combination, with a register, and a single operating mechanism, of an operating-rod connected to said operating mechanism, and means carried by said operating-rod for imparting two distinct movements to said operating mechanism, substantially as described.
- 20 8. In an apparatus of the character described, the combination, with a register, and an operating mechanism therefor, of an operating-rod connected to said operating mechanism, an operating-handle secured to said operating-rod and adapted to rotate the same about its longitudinal axis to impart a longitudinal movement to said operating mechanism, and means operated by said handle for imparting a rotary movement to said operating mechanism, substantially as described.
- 25 9. In an apparatus of the character described, the combination, with a register, and an operating mechanism therefor, of an operating-rod connected to said operating mechanism, a bracket carried by said operating-rod and having a bearing-aperture therein transverse to said operating-rod, a handle journaled in said bearing-aperture and adapted to be rotated about a transverse axis to rotate said operating-rod and impart a longitudinal movement to said operating mechanism and to be rotated in said bearing-aperture to impart a rotary movement to said operating mechanism, substantially as described.
- 30 10. In an apparatus of the character described, the combination, with a register, and operating mechanism therefor, of an operating-rod connected to said operating mechanism, an operating-handle carried by
- same about its longitudinal axis to impart a longitudinal movement to said operating mechanism, a rod parallel with said operating-rod and connected with said operating mechanism, and means controlled by said operating-handle for actuating said rod to impart a rotary movement to said operating mechanism, substantially as described.
- 70 11. In an apparatus of the character described, the combination, with a register, operating mechanism therefor, and a gear carried by said operating mechanism, of an operating-rod connected to said operating mechanism, a handle carried by said operating-rod and adapted to rotate the same about its longitudinal axis to impart a longitudinal movement to said operating mechanism, a rod substantially parallel with said operating-rod, a rack carried by said rod and engaging the gear on said operating mechanism, and means carried by said operating-handle for actuating said rod to impart a rotary movement to said operating mechanism, substantially as described.
- 75 12. In an apparatus of the character described, the combination, with a register, operating mechanism therefor, and a gear carried by said operating mechanism, of an operating-rod connected to said operating mechanism, a handle carried by said operating-rod and adapted to rotate the same about its longitudinal axis to impart a longitudinal movement to said operating mechanism, a pinion carried by said operating-handle, a rod substantially parallel to said operating-rod, a rack carried by said rod and engaging the gear on said operating mechanism, a second rack carried by said operating-rod and adapted to be engaged by the pinion on said operating-handle to actuate said rod to impart a rotary movement to said operating mechanism, substantially as described.
- 80 13. In an apparatus of the character described, the combination, with a register, operating mechanism therefor, and a gear carried by said operating mechanism, of an operating-rod, an arm carried by said operating-rod and connected at its outer end to said operating mechanism, a bracket carried by said operating-rod and having a bearing-aperture therein transversely of said operating-rod, an operating-handle journaled in said bearing-aperture, a pinion carried by said operating-handle, a rod extending substantially parallel with said operating-rod, a rack carried by said rod and engaging the gear on said operating mechanism, a second rack carried by said rod adapted to be engaged by the pinion on said operating-handle, said operating-handle being adapted to be rotated about a transverse axis to rotate said operating-rod to impart a longitudinal movement to said operating mechanism and to be rotated about its longitudinal axis to actuate said rod and impart a rotary movement to
- 85 90 95 100 105 110 115 120 125 130

said operating mechanism, substantially as described.

14. In an apparatus of the character described, the combination, with a register, operating mechanism therefor, and a gear carried by said operating mechanism, of an operating-rod, an arm carried by said operating-rod and connected at its outer end to said operating mechanism, a handle secured to 10 said operating-rod and adapted to rotate the same to impart a longitudinal movement to said operating mechanism, a rod substantially parallel to said operating-rod, a longitudinally-slotted rack-bar secured at one end 15 to said rod, a guide-lug carried by the arm of said operating-rod and engaging the slot in said rack-bar, and means controlled by said operating-handle for actuating said rod to impart a rotary movement to said operating 20 mechanism, substantially as described.

15. In an apparatus of the character described, the combination, with a register, and an operating mechanism therefor, of an operating-rod connected to said operating 25 mechanism, an operating-handle carried by said operating-rod and adapted to rotate said operating-rod to impart a longitudinal movement to said operating mechanism, means controlled by said operating-handle 30 for imparting a rotary movement to said operating mechanism, and a spring connected to said operating-rod and adapted to return the same and the operating mechanism to their normal position, substantially as de- 35 scribed.

16. In an apparatus of the character described, the combination, with a register, and an operating mechanism therefor, supports having bearing-apertures therein, an operating-rod journaled in said bearing-apertures, and means carried by said operating-rod for imparting both a longitudinal and a rotary movement to said operating mechanism, a collar carried by said operating-rod, and a 40 spring coiled about said rod and having one end secured in one of said supports and its opposite end secured to said collar, substantially as described.

17. In an apparatus of the character described, the combination, with a register, an actuating medium and an operating mechanism connecting said actuating medium with said operating mechanism, of means for actuating said medium to actuate said operating mechanism to indicate a particular fare and to register that fare, and an indicator controlled by said actuating means, substantially as described.

18. In an apparatus of the character described, the combination, with a register, an actuating medium and an operating mechanism connecting said actuating medium with said operating mechanism, of means carried by said actuating medium for imparting a 65 rotary movement to said operating mechan-

ism to set said register to indicate a particular fare, and means for imparting a longitudinal movement thereto to register that fare, and an indicator controlled by the means for imparting a rotary movement to said operating mechanism, substantially as described. 70

19. In an apparatus of the character described, the combination, with a register, and operating mechanism therefor, of an operating-rod connected to said operating mechanism, an operating-handle carried by said operating-rod and adapted to impart both a rotary and longitudinal movement to said operating mechanism, and an indicator mechanism controlled by said operating-handle, substantially as described. 75 80

20. In an apparatus of the character described, the combination, with a register, and operating mechanism therefor, of an operating-rod connected to said operating mechanism, a handle mounted on said rod and adapted to rotate the same to impart a longitudinal movement to said operating mechanism, a rod substantially parallel to said operating-rod and connected to said operating 90 mechanism, means carried by said handle for actuating said rod to impart a rotary movement to said operating mechanism, and an indicator con roll d by the movement of said rod, substantially as described. 95

21. In an apparatus of the character described, the combination, with a register, and operating mechanism therefor, of an operating-rod connected to said operating mechanism, an operating-handle carried thereby and 100 adapted to rotate the same to impart a longitudinal movement to said operating mechanism, a rod substantially parallel to said operating-rod and connected to said operating 105 mechanism, means controlled by said operating-handle for actuating said rod to impart a rotary movement to said operating mechanism, an indicator-plate located near said rod, and a pointer adapted to travel over the 110 face of said plate and controlled by said rod, substantially as described.

22. In an apparatus of the character described, the combination, with a register, and operating mechanism therefor, of an operating-rod connected to said operating mechanism, an operating-handle mounted on said rod and adapted to rotate the same to impart a longitudinal movement to said operating mechanism, a rod substantially parallel to said operating-rod and connected to said operating 115 mechanism, means controlled by said operating-handle for actuating said rod to impart a rotary movement to said operating mechanism, an indicator-plate, and a pointer carried by said rod and adapted to travel over the face of said plate, substantially as described. 120

23. In an apparatus of the character described, the combination, with a register and operating mechanism therefor, of an operat- 130

ing-rod connected to said operating mechanism, a handle mounted on said operating-rod and adapted to rotate the same to impart a longitudinal movement to said operating mechanism, a rod substantially parallel to said operating-rod, and connected to said operating mechanism, means controlled by said operating-handle for actuating said rod to impart a rotary movement to said operating mechanism, a series of indicator-plates located adjacent to said rod, and pointers carried by said rod and adapted to travel over the faces of said plates, substantially as described.

24. In an apparatus of the character described, the combination, with a register, and operating mechanism therefor, of an operating-rod connected to said operating mechanism, a handle mounted on said rod adapted to rotate the same to impart a longitudinal movement to said operating mechanism, a rod substantially parallel to said operating-rod and connected to said operating mechanism, means controlled by said operating-handle for actuating said rod to impart a ro-

tary movement to said operating mechanism, 25 an indicator-plate mounted on said operating-rod and adapted to rotate therewith, and a pointer adapted to travel over the face of said indicator-plate and to be controlled by the movement of said rod, substantially as 30 described.

25. In an apparatus of the character described, the combination, with a register, and operating mechanism therefor, of means for actuating said operating mechanism, an indicator-plate, and a pointer for said indicator-plate controlled by said operating mechanism, said pointer comprising a rectangular frame having inwardly-extending projections on the upper and lower sides thereof and 35 a downwardly-extending projection from the lower side thereof, substantially as described.

In testimony whereof I affix my signature in presence of two witnesses.

DAVID B. WHISTLER.
